UNITED STATES PATENT OFFICE

HORACE T. DYER, OF NEW YORK, N. Y., AND HERMAN R. LIEBERT AND FILLMORE D. SWAN, OF AKRON, OHIO, ASSIGNORS TO GOODYEAR-ZEPPELIN CORPORATION, OF AKRON, OHIO, A CORPORATION OF DELAWARE

MOORING MAST

Application filed June 24, 1931. Serial No. 546,520.

This invention relates to a method of and apparatus for manipulating airships and analogous lighter-than-air craft and it has for its principal object to facilitate the handling of airships, at the same time greatly reducing the personnel heretofore required in such operation.

Generally stated, the method consists of anchoring both extremities of an airship to mobile fore and aft mooring devices and moving both devices and the airship concurrently, so that in docking an airship, for example, the mooring devices and ships may be aligned with a dock, and both the mooring devices and ship moved into the dock.

The apparatus used in carrying out the method consists of a particular type of mobile or traveling mooring mast whereby the ship may be readily moved from one point to another while being held in bounds and yet is permitted a limited fore and aft movement relatively to the masts and has free angular play about a horizontal axis at its point of attachment to the masts. The improved masts, as above noted, are mobile, and with this end in view, may be mounted to travel on track-ways or may be of the tractor type and provided with suitable treads such as those used on the well known caterpillar type of tractor.

To gain a more complete understanding of the invention reference is had to the accompanying drawings, wherein

Fig. 1 is a view, in side elevation, of a type of mobile mast which may be adopted in carrying out the method;

Fig. 2 is a view in front elevation;

Fig. 3 is a plan view thereof;

Figs. 4, 5 and 6 are, respectively, views in side and front elevation and plan of another form of mast for carrying out the method;

Fig. 7 is a view in perspective, showing a method of berthing an airship in accordance with the invention and

Fig. 8 is a view, in side elevation, of a modified form of the cup and cone mounting illustrated in Figs. 1, 2 and 3.

The reference numeral 5 designates the top supporting frame of the mast embodying the

invention, and 6 the end of an airship, which, as will be understood, is suitably designed and strengthened to withstand the loads or stresses imposed thereon. The frame 5 is shown in Fig. 7 as being mounted on a suitable car or the like, generally indicated at 4 so that it may be moved from point to point as desired, it being understood, of course, that the said frame could be adapted for travel on a track or other means whereby the mast is rendered mobile. The end 6 of the ship is provided with a cone cup 7 which is journalled as at 7a, which cone fitting serves as a means of attachment in a manner well understood in the art.

A platform 501 is rotatably mounted on the top of the frame 5, preferably through the agency of a ball race 502 and retaining arms 503. Suitable means are preferably provided whereby the platform 501 may be rotated with respect to the frame 5, which may take the form of a rack 504 secured to the platform 501, which rack is engaged by a pinion 505 secured to an operating wheel 506 by a shaft 507.

A carriage 8 is mounted for limited athwartship movement on the platform 501, said carriage being provided with wheels or rollers 9 adapted for travel in guide tracks 10, which are fixed to and extend in an athwartship direction on the platform 501 and restrain the carriage from any appreciable vertical movement. At an intermediate point the carriage is provided with bearing rollers 11 adapted to bear against a further guide member 12 and restrain any fore and aft movement of the carriage.

It will thus be seen that the carriage 8 may be moved only in an athwartship direction. This movement is controlled by means of a handwheel 13, which is secured on a vertical shaft 14 having secured on the lower end thereof a bevel gear 15, which is in mesh with gears 16 and 16a secured on the shafts 17 and 17a, the shaft 17 extending through a suitable slot in the guide member 12.

Extending at substantially right angles to the shafts 17, 17a, are threaded shafts 18 and 18a, (note Figs. 2 and 3) mounted in bear-

ings 19. The threaded portions of these shafts engage threaded lugs or nuts 20 secured on the carriage 8, and said shafts have secured on one end thereof bevel gears 21 and 21^a which mesh with gears 22 and 22^a secured on the shafts 17 and 17^a.

When it is desired to move the carriage 8 in an athwartship direction, the handwheel 13 is rotated, and through the drive connections above described, rotation is imparted to the thread shafts 18 and 18^a, which engage in the thread lugs or nuts 20 secured to the carriage.

In addition to the carriage 8, and movable at substantially right angles with respect thereto, or in a fore and aft direction, a carriage, generally indicated at 23, is provided. This carriage is mounted on rollers 24 adapted to travel in guide tracks 25, which restrain any appreciable vertical movement of the carriage, and to restrain the carriage against side movement, the latter is provided with additional bearing rollers 26 adapted to bear against the tracks 25 (note Fig. 3). Stops 27 are provided at the ends of the track rails 25 to prevent over-running of the carriage 23.

It will be observed that the carriage 23 is movable only in a fore and aft direction with respect to the athwartship traveling carriage 8. This movement is controlled by means of a handwheel 28, which is mounted on a vertical shaft 29, the latter being provided with a worm 30, which meshes with a worm wheel 31 secured on a shaft 32. On the platform or under the frame of the carriage 23 is a rack 33, and the shaft 32 extends across and is provided with a gear 32^a which meshes with said rack.

By rotating the handwheel 28, the carriage 23 may be moved in a fore and aft direction as desired.

To permit the carriage 23 to have free movement with the end of the ship, as is sometimes desirable, the handwheel shaft 29 is set in an eccentric bushing 34. By rotating this bushing through the agency of an operating handle 34^a provided for this purpose, the worm 30 may be released from driving engagement with the worm wheel 31 and the carriage will then have a free floating movement or may be pushed or pulled by hand.

The invention contemplates providing limit switches (not shown) at the ends of free travel of the carriage 23, which switches operate warning signals or which switches may be adapted to operate the means for supporting the carriage to move the mast to keep the carriage 23 somewhere near the middle of its travel.

A further carriage 35, which in the form illustrated in Figs. 1, 2 and 3 travels at an incline with respect to the carriages 8 and 23, is provided, and it is to this carriage that the end of the airship is moored. Mounted at an incline on the carriage 23 are guide tracks

or rails 36 which may be shaped substantially similar to the guide rails 10 and 25, the carriage 35 being provided with rollers 37 adapted for travel in said tracks 36.

The carriage 35 is controlled by means of a handwheel 38, which is secured on a shaft 39, the latter being provided with a worm 40 in mesh with a worm wheel 41, which is secured on the one end of a threaded shaft 42, said shaft being threaded through a lug or nut 43 secured to the carriage 35.

The carriage 35 is fitted with a cross head 44, which is mounted to pivot about a horizontal axis, said head being provided with trunnions which are mounted in bearings 45 attached to the carriage frame. On its outer extremity the head 44 carries a cone connection 46 adapted to engage in the hollow cone cup 7 on the end of the ship 6, and at its inner extremity the said head terminates in counterweights 47, for counterbalancing the cone 46. It will be apparent that the ship may carry the cone 46 while the mast carries the cup 7, if desired.

In the modified form of cup and cone connection illustrated in Fig. 8, the cup 701 and cone 461 are adapted to be engaged in a vertical direction. In this construction the necessity of providing a rotatable platform 501 on the frame 5 is eliminated inasmuch as a rotatable connection may readily be provided between the cup 701 and cone 461. The cup 701 is mounted by vertically adjustable means 702 to the carriage 23 which is formed flat. In this construction the carriage 34 is dispensed with.

The improved mast may be used either as a bow or tail mast, and may be operated in a manner substantially as follows:

When the mast is used as a bow mast, it is placed in the landing field adjacent the airship dock in a position such as that indicated at "A" in Fig. 7, so that the ship may land into the wind, which will allow the ship to be more easily handled and controlled. The ship is moved slowly up to a position where the bow or nose thereof is adjacent or slightly above the mast. It is possible to bring the bow of the ship into direct engagement with the mast in several ways which may include dropping a cable from the nose of the ship, which cable is wound up by a suitable winch (not shown) on the mast and the method requiring a very small ground crew. Another method of bringing the bow of the ship into engaging relation with the mast is by the aid of ground crews controlling the ship by hand lines. The exact position of the cone 46 carried by the mast can be controlled and adjusted by means of the various handwheels 506, 13, 28 and 38, to facilitate the connection between the ship and the mast. The journals 7^a of the cone fitting 7 allow the airship to rotate about a horizontal axis.

When the mast is used as a tail mast, or when a second mast is employed in conjunction with the first, one being at the bow and the other at the tail of the ship, the procedure is the same as that described above except that in addition the tail of the ship will be secured to the tail mast. This is accomplished by moving the tail mast to a position such as indicated at "B" in Fig. 7, adjacent the tail of the ship, the ship being held by the bow mast in a fairly steady position, inasmuch as it is heading into the wind. The position of the cone of the tail mast is now adjusted until the connection to the tail of the ship is completed. To facilitate making the connection, a cable may be dropped from the tail which can be wound up on a suitable winch (not shown) on the tail mast. Or again, ground crews with hand lines from the ship may be used for this purpose.

After the airship has been anchored between the two masts in the manner above described, the mast securing the tail of the ship is swung on an arc about the mast securing the bow of the ship to align the airship with the dock, whereupon the masts and the airship are moved together into the dock.

The rotatable mounting of the platform 501 on the frame 5 allows the rotative movement of the masts and the ships as described. After the ship is secured between the two masts, it may be desirable to operate the handles 34^a to allow the carriage 23 free movement on the carriage 8 so that any small variations in the distance between the masts will not result in strain upon the airship.

If the same length airship is being handled continuously, the preferred manner of installation comprises the provision of a straight track C extending on a line out of the dock and a circular track D, all points of which are equidistant from the station A, at which station the bow mast is placed prior to landing of the ship. In this construction the masts may be readily mounted on suitable cars 4 supported on the tracks, whereby the operations above described are facilitated.

Where airships of various lengths are being handled it will probably be found desirable to replace one or both of the cars 4 with a caterpillar tractor. The operation with the masts mounted on the caterpillar tractors is the same as that described above with respect to the masts when mounted on cars running on tracks.

The hereinbefore described type of mast construction enables an airship to be manipulated with greater facility than has heretofore been possible and at the same time materially reduces the personnel required on the field. The construction is also greatly sim-

plified and improved with respect to prior known types.

Figs. 4, 5 and 6 illustrate another form of mast construction for accomplishing the results obtained by the mast shown and described in connection with Figs. 1, 2 and 3.

Referring to these figures, the frame 5 of the mast is preferably rotatably mounted on a base 491, which in turn is secured to a suitable tractor, car or other transporting device, as in the previous construction. The means for securing the frame 5 to the base 491 may take the form of a ball race 492 and retaining arms 493 provided with rollers 494. In order to positively control the position of the frame 5 on the base 491, a rack 495 may be secured to the frame 5, which cooperates with a pinion 496 secured to a shaft 497 provided with a handwheel 498, which shaft is journaled in the base 491, as at 499.

To the frame 5 a vertical framework, generally indicated at 50, having guide rails 50^a at the corners thereof, is secured. In these guide rails a vertically traveling carriage 51 provided with rollers 52 has movement. The carriage 51 is moved vertically by any suitable means which may comprise threaded shafts 53, which are journaled at their opposite ends in bearings 54 fixed to cross frames forming part of the framework 50. These shafts are threaded through nuts or lugs 55 secured to the carriage 51, so that by rotating said shafts the carriage is moved up or down, as desired. To this end a handwheel 56 is provided which is geared to the shafts 53 through the medium of a shaft 57 and gears 58.

To facilitate its operation, the carriage 51 may be counterbalanced in any well-known manner if desired.

The top of the carriage 51 has mounted for horizontal travel thereon in an athwartship direction another carriage 59, the upper structure of the carriage 51 being provided with horizontal guide rails 60 which extend in an athwartship direction, and bearing against these rails are sets of bearing rollers 61 disposed at substantially right angles and supporting the carriage 59.

The carriage 59 is controlled by means of a handwheel 62 which has a geared connection through the medium of shaft 63 and gears 64 with threaded shafts 65, the latter being threaded through nuts or lugs 66 secured to the carriage 59.

The carriage 59 is comprised of a skeleton framework or guideway which extends in a fore and aft direction and is provided with guide rails 67 in which a further carriage 68 provided with bearing rollers 69 is adapted to travel.

This carriage 69 is controlled by means of a handwheel 70 secured on a shaft 71 provided with a worm 72, which meshes with a worm wheel 73 secured on a cross shaft 74.

having a geared connection with a rack 75 fixed to the carriage 68. The worm 72 is mounted in an eccentric bushing so that it may be engaged or disengaged at will, as in 5 the case of the worm 30 hereinbefore described.

The carriage 59 has mounted on the forward end thereof a hollow cone 76 adapted to receive a cone 77 carried by a shaft 78 10 mounted in bearings 79, the said shaft and bearings being secured in the end 6 of the ship.

It will be obvious that the mast illustrated in Figs. 4, 5 and 6, although differing in 15 details of construction, will produce the same advantageous results as the mast illustrated in Figs. 1, 2 and 3. To align the mast vertically with the tail of the ship, the handwheel 56 is turned, while lateral or athwartship 20 alignment is obtained by turning the handwheel 62, the cones 76 and 77 then being engaged by turning the handwheel 70, whereupon the worm wheel 73 and the end of the ship are free for a range of backward and 25 forward movement limited only by the length of the carriage 68.

What we claim is:

1. A method of manipulating airships which comprises anchoring the bow of an 30 airship to a mobile mooring device, anchoring the stern of the airship to a second independently mobile mooring device and moving both mooring devices and the airship concurrently.

35 2. A method of berthing an airship in a dock which comprises anchoring the bow of the airship to a mobile mooring device, locating the mooring device in alignment with the dock, anchoring the stern of the airship 40 to a second independently mobile mooring device, aligning both mooring devices and the airship with the dock, and moving the mooring devices and the airship into the dock.

45 3. Mooring apparatus for aircraft comprising a supporting base, cooperating carriage members mounted for relative controllable movement in an athwartship and fore and aft direction with respect to the ship 50 to be moored, means for attaching the ship to the apparatus, a supporting carriage for said last named means, and means for adjusting said latter carriage independently of said first named carriage members.

60 4. Mooring apparatus for aircraft comprising a supporting base, a pair of cooperating carriage members mounted for relative controllable movement in an athwartship and fore and aft direction with respect to the ship to be moored, another carriage member supported by one of said first named carriages and adapted to be positioned vertically with respect to the ship, means for attaching the ship to said last named carriage,

and means for rotatably supporting all of the carriages on the base.

5. Mooring apparatus for aircraft comprising a supporting base, cooperating carriage members mounted on said base, means for imparting relative movement to said carriage members in an athwartship and fore and aft direction with respect to the ship to be moored, a further carriage member mounted on one of said first-named carriages, means 70 for positioning said last-named carriage vertically with respect to the ship, means for attaching the ship to said latter carriage, and means for releasing one of said carriages to allow it to have free relative movement longitudinally of the axis of the ship.

6. A mobile mooring mast for aircraft comprising a movable support, a pair of cooperating carriage members mounted on said support, means for shifting said carriage members to relative positions in an athwartship and fore and aft direction with respect to the ship to be moored, another carriage member supported by one of said first-named carriage members, means for raising and lowering said latter carriage, and means for attaching the ship thereto.

7. A mobile mooring mast for aircraft comprising a movable supporting base, cooperating carriage members mounted on said base, means for driving said carriages in relative vertical, horizontal and lateral planes with respect to the ship to be moored, and means for releasing the drive of one of said carriage members to permit the latter to have free movement in a plane parallel to the longitudinal axis of the ship.

8. A mobile mooring mast for aircraft comprising a main mobile supporting base, frame structures supported on said mobile base, means for independently shifting said structures in planes athwartship, fore and aft, and up and down, with respect to the ship to be moored, means to release one of said structures to allow it to have limited free travel in a plane parallel to the longitudinal axis of the ship, and means for attaching the ship to the topmost of said frame structures so that the ship may have rotational movement about a horizontal axis.

9. A mobile mast for mooring aircraft comprising a main mobile supporting base, guide rails mounted on said base, a carriage mounted for travel in said guide rails, guide rails on said carriage, a second carriage 120 mounted for travel in said latter guide rails, another carriage mounted in guide rails on said second-named carriage, means for attaching the ship to be moored to said latter carriage, means for independently adjusting 125 said carriages in planes normal to and parallel with the longitudinal axis of the said ship, and means for rotatably supporting all of the carriages on the base.

10. A mobile mooring mast for aircraft 130

comprising a main supporting base, a carriage mounted on said base, a second carriage mounted on said first-named carriage, a third carriage mounted on said second-named carriage, means for independently adjusting said carriages in directions athwartship, fore and aft, and up and down with respect to the ship to be moored, means for attaching the ship to the topmost of said carriages, means to release one of said carriages to allow it to have a limited free travel in a direction longitudinally of the ship, and means rotatably supporting the mast.

11. A mobile mast for aircraft comprising a main mobile supporting base, lower, intermediate and upper independently movable members mounted on said base, means for attaching the ship to be moored to said upper member, means for independently adjusting said members in horizontal, vertical and lateral planes, and means to release the adjusting means on said intermediate member to allow it to have free movement longitudinally of the ship.

12. A mooring mast for aircraft comprising a main supporting base, a carriage mounted on said base, means for driving said carriage in an athwartship direction, a second carriage mounted on said first-named carriage, means for driving said carriage in a fore and aft direction, a third carriage mounted on said second-named carriage, means for driving said carriage in an up and down direction, means for attaching one extremity of the ship to said last-named carriage, means for releasing the drive on said second-named carriage, and means in the connection between the ship and the mast to allow rotation of the ship about the mast as a vertical axis.

13. Mooring equipment for aircraft comprising a mobile mooring mast adapted to be attached to the bow of the ship to be moored, another mobile mooring mast adapted to be attached to the tail of the ship, one of said masts being provided with independently movable frame structures, means for adjusting said structures in planes extending athwartship, fore and aft, and up and down with respect to the ship, and means for releasing one of said frame structures to permit the ship to have free fore and aft movement with respect to the mast.

14. A mobile mast for aircraft comprising a main supporting base, lower, intermediate and upper independently movable frame structures mounted on said base, means for attaching the ship to be moored to said upper frame structure, and means for independently adjusting said frame structures in horizontal, vertical and lateral planes, one of said frame structures being releasable to permit the ship to have limited free movement longitudinally of the ship.

15. A mast for aircraft comprising a main

supporting base, lower, intermediate and upper independently movable frame structures mounted on said base, means for attaching the ship to be moored to said upper frame structure, means for independently adjusting said frame structures in horizontal, vertical and lateral planes, swivel means in the attaching means to allow the ship to have free rocking movement about its horizontal axis and means in the connection between the ship and the mast to allow movement of the ship about the mast as a vertical axis.

16. The combination with an airship having a mooring attachment in one end thereof, of a mobile mooring mast provided with a horizontally and vertically pivoted anchor member adapted to engage said attachment, a carriage for supporting said anchor member on the upper extremity of the mast, a pair of cooperating, relatively adjustable carriages for supporting said first-named carriage, and means for independently adjusting each of said carriages to position the anchor member with respect to said attachment when attaching the ship to the mast.

17. The combination with an airship having a mooring attachment of a mobile mooring mast provided with a horizontally pivoted anchor member adapted to engage said attachment, a carriage for supporting said anchor member on the upper extremity of the mast, a pair of cooperating, relatively adjustable carriages for supporting said first-named carriage, and means for independently adjusting each of said carriages to position the anchor member with respect to said attachment when attaching the ship to the mast, one of said carriages being releasable after the ship is attached to permit the ship to have unrestricted play relatively to the mast in a plane substantially longitudinally of the ship.

18. A method of berthing an airship which comprises aligning a mobile mooring mast with an airship dock, landing the airship into the wind to bring the bow thereof adjacent the mast, securing the bow of the ship to the mast, bringing another independently mobile mast adjacent the tail of the ship as it floats out behind the bow mast held substantially in position by the wind, securing the tail of the ship to the last-named mast, swinging the last-named independent mast, on an arc about the first-named mast to align the ship with the dock, and moving the masts together with the ship into the dock.

19. In combination an airship and a pair of anchoring masts, means for making each of the masts independently movable, one of said masts being rigidly secured adjacent each end of the airship, and means on one of the masts whereby the mast and the airship can have relative longitudinal movement.

20. In combination an airship, a bow mast, means for anchoring the bow of the airship to

the bow mast, rolling means mounting the bow mast whereby it can be moved as desired, a stern mast, means for anchoring the stern of the airship to the stern mast, said stern mast being entirely independent of the bow mast, rolling means on the stern mast whereby it can be independently moved as desired, and means in the connections between the masts and the airship whereby the airship can have 10 rolling movement about a horizontal axis.

21. In combination an airship, a bow mast, means for anchoring the airship to the bow mast, rolling means mounting the bow mast whereby it can be moved as desired, a stern 15 mast, means for anchoring the airship to the stern mast, said stern mast being entirely independent of the bow mast and inovable around the bow mast, and rolling means on the stern mast whereby it can be independently 20 moved as desired.

22. In combination an airship, a bow mast, means for anchoring the airship to the bow mast, rolling means mounting the bow mast whereby it can be moved as desired, a stern 25 mast, means for anchoring the airship to the stern mast, said stern mast being entirely independent of the bow mast, and movable around the bow mast, rolling means on the stern mast whereby it can be independently 30 moved as desired, and means in the masts for adjusting the anchoring means thereof in a plurality of directions whereby the anchoring 35 of the airship is facilitated.

23. In combination an airship, a bow mast, 40 means for anchoring the airship to the bow

mast, a stern mast, means for anchoring the airship to the stern mast, said stern mast being entirely independent of the bow mast, and means in the masts for adjusting the anchoring means thereof in a plurality of 70 directions whereby the anchoring of the airship is facilitated.

24. In combination in land airship handling mechanism a housing dock, an airship, a bow mast to which the bow of the airship can be substantially rigidly anchored, means for rendering the bow mast movable into and out of the dock, means for anchoring the stern of the airship, means on the stern anchoring means for rendering the same independently 75 movable as desired whereby the airship can be moved into and out of the dock and anchored and released with facility.

25. A method of berthing an airship which comprises aligning a mobile mooring mast with an airship dock, nosing the bow of the airship up to the mast while landing the ship into the wind, fixing the bow of the ship to the mast, securing means to the rear portion 80 of the ship as it floats out behind the bow mast while held substantially in position by the wind, swinging it on an arc about the mast by said last mentioned means to align the ship with the dock, and moving the mast, rear 85 securing means and ship together into the dock.
